(57) **CLAIM**

The ornamental design for a jacket, as shown and described.

DESCRIPTION

FIG. 1 is a perspective view of a jacket showing my new design in an in-use configuration;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines immediately adjacent to the shaded area represent unclaimed boundaries of the design. The contrast in shading represents a contrast in appearance only and does not represent any particular color, material, texture or finish. The unshaded geometric regions within the claimed area, demarcated by the broken line showings, are for environmental purposes only and form no part of the claimed design. The broken lines showing the remainder of the jacket are for environmental purposes only and form no part of the claimed design.
